FIG. 1

FIG. 2

FIG. 3

FIG. 4

FIG. 5

FIG. 6

FIG. 1 is a side elevational view of a cup or similar article embodying my new design;

FIG. 2 is a side elevational view thereof, illustrating the opposite side of FIG. 1;

FIG. 3 is a top plan view thereof;

FIG. 4 is a bottom plan view thereof;

FIG. 5 is an end elevational view thereof; and

FIG. 6 is an end elevational view thereof illustrating the opposite side of that shown in FIG. 5.

The design is characterized by the series of corrugations on the body extending from the bottom of the cup or similar article substantially three-fourths the height thereof in combination with a handle of the configuration

shown, having corrugations extending over the entire surface thereof.

I claim:

The ornamental design for a cup or similar article, as shown and described.
